US0D1071366S

(12) **United States Design Patent** (10) **Patent No.:** **US D1,071,366 S**
(45) **Date of Patent:** **** Apr. 15, 2025**

(54) **HEARING PROTECTOR**

(71) Applicant: **TECMEN ELECTRONICS CO., LTD**, Jiangsu (CN)

(72) Inventor: **Ziqian Wu**, Nanjing (CN)

(73) Assignee: **TECMEN ELECTRONICS CO., LTD**, Nanjing (CN)

(**) Term: **15 Years**

(21) Appl. No.: **29/818,050**

(22) Filed: **Dec. 6, 2021**

(30) **Foreign Application Priority Data**

Jun. 4, 2021 (CN) 202130343510.X

(51) **LOC (15) Cl.** **29-02**

(57) **CLAIM**

The ornamental design for a hearing protector, as shown and described.

DESCRIPTION

FIG. 1 is a front perspective view of a hearing protector showing my new design;

FIG. 2 is a front elevation view of the hearing protector of FIG. 1;

FIG. 3 is a rear elevation view of the hearing protector of FIG. 1;

FIG. 4 is a right side view of the hearing protector of FIG. 1;

FIG. 5 is a left side view of the hearing protector of FIG. 1; FIG. 6 is a top view of the hearing protector of FIG. 1; and, FIG. 7 is a bottom view of the hearing protector of FIG. 1. The broken lines shown in the drawings represent portions of the hearing protector that form no part of the claimed design.

1 Claim, 7 Drawing Sheets
